UNITED STATES PATENT OFFICE.

OTTO SCHWEIZER, OF PATERSON, NEW JERSEY.

WASHTUB ATTACHMENT.

SPECIFICATION forming part of Letters Patent No. 669,860, dated March 12, 1901.

Application filed July 31, 1900. Serial No. 25,389. (No model.)

To all whom it may concern:

Be it known that I, OTTO SCHWEIZER, a citizen of the United States, and a resident of Paterson, in the county of Passaic and State 5 of New Jersey, have invented a new and Improved Washtub Attachment, of which the following is a full, clear, and exact description.

The purpose of this invention is to provide 10 a washtub with a removable partition enabling the washtub to be used as a bath-tub; and my invention consists in certain novel features of construction of the partition and its appurtenant parts.

15 This specification is the disclosure of one form of the invention, while the claims define the actual scope thereof.

Reference is to be had to the accompanying drawings, forming a part of this specification, 20 in which similar characters of reference indicate corresponding parts in all the views.

Figure 1 is a perspective view of a wash-tub having the invention applied thereto. Fig. 2 is a cross-sectional view thereof, showing 25 the partition fastened in place. Fig. 3 is a section on the line 3 3 of Fig. 2. Fig. 4 is a cross-section of the invention, showing the levers released and the levers when the strain thereon is relaxed and the levers are about 30 to be disengaged from the tub. Fig. 5 is an enlarged view of the levers as in Fig. 4. Fig. 6 is a detail view of the same parts, except that the levers are shown in disengaged position. Fig. 7 is a section on the line 7 7 of 35 Fig. 6. Fig. 8 is a detail section illustrating the manner of packing the partition, and Fig. 9 is a similar view of a modified arrangement of the packing.

The tub *a* is preferably constructed of slate 40 in the usual manner and is sustained on legs *a'*, as shown. At each side of the middle of the tub cleats *b* of metal are arranged, the lower ends of the cleats being formed with feet *b'*, which are fastened to the middle legs *a'* of the 45 tub. The upper ends of the cleats *b* are formed with inwardly-projected lips *b*², which are set into recesses in the side walls of the tub, so as to secure the upper ends of the cleats thereto. The cleats are also formed at their upper 50 ends with inwardly-projecting flanges *b*³, the purpose of which will fully appear herein-after.

The partition *c* is constructed, preferably, of metal and is provided at its bottom and side edges with a rubber packing-strip *c'*, the 55 ends of which are fastened at the upper ends of the side edges of the partition by metallic clips *c*², secured by screws or otherwise to the top edge of the partition. Corner-pieces *d* are set in the tub at the bottom thereof, so 60 as to receive the lower corners of the partition *c*, and thereby securely pack the partition at these points to prevent water leaking past the partition. If desired, the partition may be provided with a pneumatic packing-tube *c*³ (see Fig. 9) in place of the strip *c'*.

The partition *c* is held firmly in place by two levers *e*, which are formed, as indicated best in Figs. 5 and 6, with longitudinally-disposed slots *e'* therein, through which slots 70 are passed headed pins *f*, fastened to the upper edge of the partition *c*. These pins serve to hold the levers in position on the partition. The outer ends of the levers *e* are formed with toes *e*², which respectively engage under the lips or flanges *b*³, so that the outer ends of the levers are thereby secured to the top of the tub through the medium of the cleats *b*, which are fast to the tub. The inner ends of the levers *e* are formed with reduced portions *e*³, which are slotted to receive a screw *g*, which passes through them and screws into the edge of the partition *c*. This screw *g* is provided with a head *g'*, formed with openings for the reception of a tool by 85 which the screw may be operated. Mounted on the screw, just above the ends *e*³ of the levers *e*, is a block *h*, which is engaged by the head *g'* of the screw and which is pressed thereby into engagement with the ends *e*³ of 90 the levers *e*, so as to actuate the levers and throw them into locked position, as shown in Figs. 2 and 3. The screw *g* has a collar *g*² formed thereon at a point below the ends *e*³ of the levers *e*, so as to limit the movement 95 of the screw through the ends of the levers. The block *h* carries at one side an apron *h'*, which hangs down alongside of the inner ends of the levers *e*. The ends *e*³ of the levers are provided with pins *e*⁴, and on one of these pins a plate *i*, forming a sort of lever, is fulcrumed. The other pin *e*⁴ is projected loosely into a slot *i*², formed in the plate *i*. By throwing the plate *i* to the position shown 100

in Figs. 2, 3, and 5 the levers *e* are extended and their toes *e*² caused to engage with the flanges *b*³. Then by screwing down the screw *g* the levers are held in engagement with the hub and the partitions fastened. (See Figs. 2 and 3.) By throwing the plate *i* to the position shown in Figs. 6 and 7 the levers *e* are moved toward each other and out of engagement with the flanges *b*³. The slot *i'* enables the levers to be quickly and easily disengaged from the tub.

To lock the partition in place, the plate *i* is thrown to horizontal position and the screw *g* is moved down until the head *g'* of the screw engages the block *h* and forces it against the ends *e*³ of the levers *e*, holding the levers in the position shown in Figs. 2 and 3. To remove the partition, the screw *g* is moved up to the position shown in Figs. 4 and 5, so that the head *g'* of the screw is out of contact with the block *h*. The plate *i* may then be thrown to the position shown in Figs. 6 and 7, whereupon the levers *e* are moved with their ends *e*² out of engagement with the flanges *b*³ and the partition *c* may be lifted out of the tub.

Having thus described my invention, I claim as new and desire to secure by Letters Patent—

1. A washtub attachment, comprising a partition, levers mounted on the upper edge 30 thereof, a plate pivoted on one lever and having sliding connection with the other lever, and a screw carried on the partition and working with the inner ends of the levers.

2. The combination with a washtub, of 35 cleats secured to the outer faces thereof and having inwardly - projecting extensions at their upper ends, such extensions being set into recesses in the tub, a removable partition fitted in the tub, and means on the partition engaging the extensions of the cleats to hold the partition in place.

In testimony whereof I have signed my name to this specification in the presence of two subscribing witnesses.

OTTO SCHWEIZER.
